UNITED STATES PATENT OFFICE.

ALBERT J. EDEN, OF MINERVA, OHIO.

MILK-CAN.

No. 897,073.

Specification of Letters Patent.

Patented Aug. 25, 1908.

Application filed July 26, 1907. Serial No. 385,651.

To all whom it may concern:

Be it known that I, ALBERT J. EDEN, a citizen of the United States of America, residing at Minerva, in the county of Stark and State 5 of Ohio, have invented certain new and useful Improvements in Milk-Cans, of which the following is a specification, reference being had therein to the accompanying drawing.

This invention relates to improvements in 10 milk cans and similar receptacles, and the invention has for its object to provide a novel milk can wherein an outer shell is used for protecting the milk can and providing a ventilating space around the same, whereby the 15 contents of the can will be maintained in a cool and healthy condition.

Another object of this invention is to provide a milk can having vents for ventilating the interior of the can, it being impossible 20 for dirt or foreign matter to enter the can through the vents thereof.

With the above and other objects in view which will more readily appear as the invention is better understood, the same consists 25 in the novel construction, combination and arrangement of parts, to be presently described and then specifically pointed out in the appended claims.

In the drawings:—Figure 1 is an elevation 30 of the milk can, partly in section, and Fig. 2 is a bottom plan of the same.

My improved milk can consists of a cylindrical body 1 having a rounding or convex bottom 2; a tapering contracted mouth 3, 35 provided with an outwardly extending flange 4. Fitting in the mouth 3 is a lid 5 carrying a dome 6 having circumferentially arranged openings 7 formed therein. In the dome is arranged a horizontal perforated partition or 40 screen 8, while the lid 5 is provided with a peripheral flange 9 adapted to rest upon the flange 4 of the can 1. Surrounding the body 1 of the can is a cylindrical shell 10 of a diameter slightly greater than the body of the 45 can, thereby providing an annular space 11 between the can 1 and the shell 10. The lower edges of the shell 10 are reinforced by reaming or by a wire 12, and riveted or otherwise secured in the lower end of the shell, as 50 at 14, are straps 15, said straps being disposed at right angles with relation to one another. The straps 15 are riveted together, and to the convex bottom 2 of the can, as at 16,

whereby the can will be firmly supported within the shell 10.

To the upper end of the cylindrical shell 10 is secured a perforated casing 17 carrying a sleeve 18 having a flared or funnel-shaped end 19. The casing 17 and the sleeve 18 are supported parallel to the mouth or upper 60 sides of the can 1, and the sleeve 18 can be soldered or otherwise secured to the flange 4, whereby the can 1 and the shell 10 are practically integral.

The diametrically opposed sides of the 65 shell 10 adjacent to the perforated casing 17 are provided with handles 20 of the conventional form. The shell 10 will protect the can from being injured or contacting with any deleterious matter, at the same time providing an annular space around the can 1 which will maintain the can in a cool condition. To insure the circulation of air in the annular space around the can 1, I provide a plurality of openings 21 adjacent the lower 70 end of the shell 10, preferably two rows circumferentially arranged, with the openings of each row staggered with relation to the openings of the other row.

The milk can or receptacle is constructed 80 of strong and durable metal, and I reserve the right to make such changes in the structural details in the construction as are permissible by the appended claim.

Having fully described my invention, what 85 I claim and desire to secure by Letters Patent is:—

A milk can comprising a can proper terminating at its upper end in an annular outwardly-extending flange, an outer shell surrounding the can and spaced therefrom, the said shell at the upper end projecting above the can and being secured to said annular flange, and supporting strips secured within the lower end of said shell above the bottom 95 thereof and forming a support for the lower end of said can, the said can being fixedly-secured to said strips, substantially as described.

In testimony whereof I affix my signature 100 in the presence of two witnesses.

ALBERT J. EDEN.
